UNITED STATES PATENT OFFICE.

DAVID W. BROWN, OF NEW YORK, N. Y.

INTENSIFIER OF HIGH-FREQUENCY ELECTRIC OSCILLATIONS.

1,235,650.

Specification of Letters Patent. Patented Aug. 7, 1917.

Application filed October 8, 1914. Serial No. 865,619.

To all whom it may concern:

Be it known that I, DAVID W. BROWN, a citizen of the United States, and a resident of the borough of Manhattan, city, county, and State of New York, have invented certain new and useful Improvements in Intensifiers of High-Frequency Electric Oscillations, of which the following is a specification.

10 This invention relates to improvements in intensifiers of high-frequency electric oscillations.

In such arts as wireless telegraphy, wireless telephony and other arts utilizing the 15 transmission of Hertzian waves through the ether from generating apparatus at a sending station to detectors at a distant receiving station, high-frequency electric oscillations (hereinafter sometimes more briefly 20 designated "oscillations") produced at said receiving station through the action of said Hertzian waves, travel along wires forming parts of circuits operatively connected with aerials at said receiving station, either directly 25 or indirectly. Said wires are in series with sensitive devices termed "detectors," which detectors are of great variety, all, however, being sensitive to high frequency electric oscillations, and said wires constitute 30 the paths by which high frequency electric oscillations reach said detectors. Said detectors are also in local circuits equipped with various indicating instruments, such as telephones, telegraphic instruments and 35 other electrically operated instruments adapted to produce or aid in producing various desired results, as operating telephones, telegraph instruments, exploding explosive substances, producing electrolytic 40 compositions and depositions, controlling the starting, stopping and operation of machinery, and accomplishing other results which can be effected through the aid of electric currents.

45 When, however, the distance from the sending to the receiving station is too great, or when, from any other cause, the oscillations which reach the detector are too feeble to properly affect said detector, the instruments in the local circuits will not be operated, and the desired results will fail of accomplishment.

It is therefore, the purpose of this invention to provide intensifiers of said oscillations, which will so intensify them that oscillations otherwise too feeble to properly

affect the detector will, when so intensified, properly affect it, and thus enable the instruments in the local circuit to be operated and the desired results attained.

Now, I have discovered that if the paths, or wires, along which the oscillations travel to the detector be surrounded by metal envelops, preferably of brass or copper, which envelops are insulated from said wires, then 60 said oscillations become intensified so that oscillations which, without said intensifiers, would be too feeble to properly affect the detector, will, with said intensifiers, be so intensified as to properly affect said detector. 70 Said envelops, or tubes, also become themselves highly electrically excited when said oscillations travel along said wires, and may be connected with other detectors, which may have their local circuits with their own 75 instruments; and thus another advantage of this invention is that it allows two detectors and two local circuits with their different instruments, to be operated through the same oscillations. Moreover, since said wires are 80 insulated from said envelops, it becomes possible to properly charge either said wires or said envelops; from a suitable source of electricity, without improperly affecting a detector connected with the wires or the envelops which are not charged. For example, 85 this invention renders it possible to electrically charge said envelops, without improperly affecting a detector which is in series with said wires, or to electrically charge said wires, without improperly affecting a detector which is in series with said envelops. Such independency of the wires and the envelops has important applications 90 in the utilization of Hertzian waves, and especially when said intensifiers are used in connection with the method of and apparatus for increasing the effect of high-frequency oscillations on detectors, which are 95 set forth in my other application for United States patent, filed October 1, 1914, Serial 100 Number 864,393.

In the accompanying drawings said oscillation intensifiers are shown as tubes completely encircling the paths of the oscillations, but it is not indispensable that said intensifiers be complete envelops around said paths; nor is it necessary that said intensifiers have a circular cross section, although the circular cross section is to be preferred. 110 Said intensifiers are also illustrated as surrounding the wires which are directly con-

nected with the detector. But as is now well known, the high frequency oscillations may pass through a coil of a transformer and the detector may be located in a circuit with the 5 other coil of the transformer and this invention equally covers both arrangements. But in all cases said oscillation intensifier tubes are to be placed as near as practicable to the detectors, and about at the positions indicated in the accompanying drawings, and said tubes are to be as small as practicable to admit said wires and yet be insulated therefrom. For the effect of the said tubes upon the high frequency oscillations depends 10 upon the proximity of the walls of the tubes to the said wires (while nevertheless being insulated from said wires) and upon the location of said tubes as near as practicable to said detectors. Said intensifiers are also 15 shown in said drawings as having straight longitudinal axes, but they may have curved longitudinal axes, the wires being similarly curved; and curved intensifiers may be preferable in cases where it is desired to have considerable length of wires and intensifiers in 20 small space. In said drawings, also, said intensifiers are shown on lateral wires which are understood to be connected directly or inductively with aerials, and said intensifiers might also be arranged on the aerials 25 themselves.

Referring to said drawings (which illustrate several modifications of my invention in a diagrammatic manner) to aid the 30 description, Figure 1 is a broken longitudinal section of an arrangement of said oscillation intensifiers, wherein the detector is in series with the said paths or wires; Fig. 2 being a cross section on the line 2-2 of Fig. 3. Fig. 3 is a broken longitudinal section of another arrangement of said intensifiers, wherein the detector is in series with said intensifiers. Fig. 4 is a broken longitudinal section of an arrangement of said intensifiers with two detectors, one detector being in series with said wires and the other in series with said intensifiers. Fig. 5 is a broken longitudinal section of an intensifier adapted to be filled with a liquid dielectric, 35 such as a suitable oil. Fig. 6 is a broken sectional detail of a modification wherein the closure of the filling orifice is provided with an expansion chamber. Fig. 7 is a cross section showing one form of support for the intensifiers. Fig. 8 is a diagrammatic detail of an intensifier consisting of a wire coil.

Referring to Fig. 1, A, B represent wires which, within the intensifiers, are preferably bare or uncovered, and which form paths of 40 oscillations set up by Hertzian waves received from sending stations distant from the receiving station. Said wires A, B are parts of closed or open circuits operatively connected with aerials at the receiving station 45 in any manner, and either directly or in-

ductively; said aerials and other parts of the said circuit not being shown in certain figures, since they are of any usual kind and arrangement, and are no part of this invention. D is a detector of high-frequency electric oscillations, and of any known kind, as a spark-gap, a coherer anticoherer, thermal detector, or any other device which will detect high frequency electric oscillations. Said detector D is in series 70 with said wires A, B, and wires of a local circuit, also in series with said detector, are indicated by wires e, f; said local circuit being provided with any desired instruments which can be operated by electric currents. 75 G and H are the intensifiers respectively arranged around said wires A and B. Said intensifiers G and H are shown as sleeves or tubes of metal, preferably brass or copper, encircling said wires A and B, but insulated 80 from them, as by spiders or notched disks l, of insulating material secured at suitable positions within said tubes G, H, and through the centers of which said wires A, B pass. Said intensifiers may be supported in 85 any suitable manner, as on standards P, which are preferably of electrical non-conducting material, as dried wood, fiber, glass or other non-conducting material.

The operation is as follows: When high-frequency oscillations set up by Hertzian waves from the sending station travel along 90 said wires A, B to and from said detector D, said tubes G, H intensify said oscillations so that they will affect said detector D more 95 powerfully than they would affect it if not so intensified; and oscillations too feeble to properly affect said detector of themselves will, when so intensified, properly affect it, and enable instruments in the local circuit 100 to be operated. Thus the distances over which Hertzian waves can be effectively transmitted from sending to receiving stations may be increased, and results otherwise unattainable can be attained at the receiving 110 station by use of said intensifiers.

Fig. 3 is a diagrammatic representation of intensifiers which are in general similar in construction and arrangement to the intensifiers illustrated in Figs. 1 and 2; but 115 said tubes G and H are now placed in series with a detector D by connecting wires a' b'; e f indicating wires of a local circuit. In this arrangement the free ends of said wires A, B are preferably not connected together, 120 but separated and tipped with metal balls as indicated.

Fig. 4 represents diagrammatically an arrangement of intensifiers G, H similar to the intensifiers illustrated in Fig. 1 but with 125 two detectors, D, D' respectively; detector D being in series with said wires A, B and detector D' being in series with said intensifiers G, H. Each said detector may be connected with its own local circuit provided 130

with its own instruments, and thus one train of oscillations traveling along said wires A, B may affect two detectors, and enable two different instruments or set of instruments to be operated. One of said detectors, as D will, in this case, be affected by the oscillations traveling on said wires A, B, and the other detector, as D', will be affected by the oscillations set up in said intensifiers 5 G H, which become intensely excited by the passage of oscillations along said wires A, B; and thus, finally as above stated, instruments in the two local circuits may operate by one train of oscillations set up by Hertzian waves 10 from the sending station.

The intensifiers illustrated in Figs. 1, 2, 15 3 and 4 contain air, but it may be desirable to fill them with another dielectric, as a suitable oil, and Fig. 5 illustrates an intensifier G' adapted to be so filled. Said intensifier G' is provided with removable caps G², G³ respectively, having centers m of insulating material through which said wires A and B pass with liquid-tight fit; said caps 20 25 G², G³ having liquid-tight fit on said intensifier G'. A filling orifice g, with suitable closure, may be provided, and it is also desirable to provide a small expansion chamber, as N, communicating with the interior of 30 35 said intensifier G' and extending to a level above the top of said filling orifice g, to provide for expansion of the oil with which said tube G' is filled, should said oil become heated. As shown in Fig. 6, the closure g' of said filling orifice may be formed with an expansion chamber, and the necessity of a separate expansion chamber may be obviated.

My said intensifiers have been illustrated 40 in the said accompanying drawings, and hereinbefore described, as consisting of continuous metal tubes, but said intensifiers may be constructed of coils of insulated wire G³, and the ends of the wires may be connected together so that said intensifiers will 45 then be in their own closed circuits.

Said intensifiers may be employed with 50 various arrangements of detectors and wires, and several such have been illustrated and described herein and also in my said other

application, Serial No. 864,393. It is however, to be understood that the invention is not limited to such arrangements but covers all arrangements of the intensifiers with detectors.

55

Now having described my improvements, I claim as my invention:

1. The combination in apparatus for receiving high frequency electric oscillations of an aerial, wires operatively electrically connected with said aerial, a detector in operative connection with said wires, and oscillation intensifiers consisting of metal envelopes substantially encircling said wires at the part thereof as near as practicable to 60 said detector but insulated from said wires.

2. The combination in apparatus for receiving high frequency electric oscillations of an aerial, wires of a circuit electrically operatively connected with said aerial, a 70 detector in said circuit, and oscillation intensifiers consisting of metal envelopes of small diameter encircling said circuit wires at positions as near as practicable to said 75 detector but insulated from said wires and disconnected from earth.

3. The combination of a detector, wires forming paths for high-frequency electric oscillations in series with said detector, oscillation intensifiers consisting of metal 80 tubes encircling said wires but insulated therefrom, and a detector in series with said oscillation intensifiers.

4. The combination of a detector, wires forming paths for high-frequency electric 85 oscillations in series with said detector, a local circuit for said detector adapted to include the usual instruments, oscillation intensifiers encircling said wires but insulated therefrom, a detector in series with said 90 intensifiers, and a local circuit and instruments in circuit with said last named detector.

Signed at New York city, in the county of New York and State of New York, this 6th 95 day of October, A. D. 1914.
